UNITED STATES PATENT OFFICE.

ORRIN HENRY SAVAGE, OF NEW YORK, N. Y., ASSIGNOR TO OAKVILLE COMPANY, OF WATERBURY, CONNECTICUT, A CORPORATION OF CONNECTICUT.

DEVICE FOR APPLYING STERILIZERS TO MOUTHPIECES.

No. 840,662.

Specification of Letters Patent.

Patented Jan. 8, 1907.

Application filed June 17, 1905. Serial No. 265,633.

To all whom it may concern:

Be it known that I, ORRIN HENRY SAVAGE, a citizen of the United States, and a resident of the borough of Manhattan, in the county 5 of New York and State of New York, have invented a new and useful Improvement in Devices for Applying Sterilizers to Mouthpieces, of which the following is a specification.

10 My invention pertains to devices for applying sterilizers to mouthpieces, and comprises improvements in the form of said devices and providing for the use of the mouthpieces without necessarily operating the sterilizing devices in order to allow free access to 15 said mouthpieces.

My invention also provides improved means whereby said devices may be readily attached to or detached from the mouth- 20 pieces.

In the drawings, Figure 1 is a side elevation of a telephone-mouthpiece, a central vertical transverse cross-section of a sterilizing device being also shown, part of the mouth- 25 piece being broken away for that purpose. Fig. 2 is a front elevation of the elements which are shown in Fig. 1; and Fig. 3 is a rear elevation of the device closed, with the mouthpiece shown in section.

30 Reference characters are relatively alike throughout the drawings.

Referring to the drawings, *a* represents a mouthpiece of a form sometimes used in combination with receivers of telephones.

35 *b* is an annulus which extends across the outer opening of the mouthpiece *a* and a part of which in the general form of the inside of the mouthpiece *a* extends inwardly of the latter. An absorbent annulus *c*, which is adapted 40 both in form and dimensions to closely surround the inwardly-extending part of the annulus *b*, is held in such position by a retaining-annulus *d*, said annulus *d* being retained in its proper position by any suitable 45 means—such, for instance, as frictional engagement of its peripheral surface with the surface of the inner wall of the annulus *b*.

A collar *e* is adapted both in form and dimensions to closely surround a part of the 50 peripheral surface of the outer wall of the mouthpiece *a* and is hinged to the annulus *b*. A suitable catch, herein shown and referred to as *f*, is firmly attached to the annulus *b*,

preferably opposite the hinge which connects the latter to the collar *e*. The latter should 55 preferably be formed of material that is at least to some extent resilient. It with the annulus *b*, to which it is hinged, forms a clamp which, the parts thereof being firmly held together by means of the catch *f*, may 60 firmly clamp the mouthpiece *a*, and thus secure the whole device in an operative position. The outer rim of the collar *e*, as shown, is inclosed within the rim of the annulus *b* when the device is secured upon the mouth- 65 piece *a* in position for use.

The operation of my invention may be readily inferred from the preceding description thereof if it be understood that a suitable sterilizing liquid be applied in a suitable 70 quantity to and be absorbed by the absorbent annulus *c* and that the sterilizing device be thereafter clamped to the mouthpiece *a* by means of the hinged collar *e*, the rim whereof engages the catch *f*. The sterilizing 75 device being positioned as thus described, with a suitable sterilizing liquid applied in sufficient quantity to the absorbent annulus *c*, the complete sterilization of the interior surfaces of the mouthpiece *a* and of the sterilizing device will be maintained until the sterilizing liquid shall either have evaporated 80 or become inert, in either of which events the device may by a slight pull be opened outwardly from the mouthpiece *a*, a new supply of sterilizing liquid may be applied to the absorbent annulus *c*, and the device may be reattached to the mouthpiece *a* by engaging the collar *e* with the catch *f*.

It should be noted that this device may be 90 used without the absorbent annulus *c* and retaining-annulus *d* if the sterilizing substance, which may, for instance, be in the form of a plastic or pasty substance, be applied directly to the surface of the inwardly- 95 extending part of the annulus *b*.

I claim as new and as my invention—

1. A device for applying sterilizers to mouthpieces and comprising an annulus which is attachable to a mouthpiece and has 100 a part which is adapted to extend inwardly of the mouthpiece and a collar which surrounds the periphery of the mouthpiece and is hinged to the annulus and with the latter clamps the device in an operative position.

105 2. A device for applying sterilizers to

mouthpieces and comprising an annulus which is attachable to a mouthpiece; an absorbent annulus which is adapted to extend inwardly of the mouthpiece, and a resilient collar which is hinged to the first-mentioned annulus; said annuli and collar being so arranged one with another as to clamp the outer extremity of the mouthpiece.

3. A device for applying sterilizers to mouthpieces and which is attachable to a mouthpiece and comprises an annulus which has a part which is adapted to extend inwardly of the mouthpiece and an absorbent

annulus which surrounds said inwardly-extending part; a collar which is hinged to the first-mentioned annulus; and a catch which is attached to said annulus, all being so arranged as to clamp the device to the outer extremity of the mouthpiece.

In testimony whereof I have signed my name to this specification in the presence of two subscribing witnesses.

ORRIN HENRY SAVAGE.
